UNITED STATES PATENT OFFICE.

HARRY C. PENDLETON, OF PIEDMONT, CALIFORNIA.

METHOD AND MEANS FOR FACILITATING SEALING DEEP WELLS.

1,393,311.

Specification of Letters Patent. Patented Oct. 11, 1921.

Application filed September 1, 1920. Serial No. 407,357.

To all whom it may concern:

Be it known that I, HARRY C. PENDLETON, a citizen of the United States, and resident of Piedmont, California, have invented 5 certain new and useful Methods and Means for Facilitating Sealing Deep Wells, of which the following is a specification.

The present invention relates to a system and means for sealing deep wells, as may 10 be necessary to prevent the inflow of water at one or more levels in the well.

As is well known, in drilling deep wells for oil for instance, strata, of material are penetrated, some of which contain water, 15 and if the well is extended below this water zone, it is desirable to support the casing of the well and to prevent the flow of water to the inlet of the well.

Diverse methods and means have heretofore been utilized for this purpose, with not altogether satisfactory results, and it is an object of the present invention to provide a novel, extremely simple and inexpensive method and means for sealing the 25 casing of the well at any levels desired during the sinking of the well. The common practice in sinking wells is to lower connected sections of metallic casings as the drilling proceeds, and, according to the conditions, casing strings of different diameter 30 are telescoped one within the other. For instance, a casing of given diameter may be sunk to a level at which there is encountered a stratum of water, and before the casing is lowered beyond that zone, it is desirable 35 to seal the bore of the well to prevent the inflow of the water into the finished well, and it is an object of the present invention to provide a method and means for 40 effecting a good seal with minimum requirement of material, time and labor.

A further object of the invention is to provide for the sealing of the well by the deposit of a charge of cementitious material 45 at the water-bearing strata and at the contiguous lower end of the well casing and to provide a good aggregate body to be embedded in the cement. It is, in this connection, an object of the invention to provide means 50 for carrying down a charge of cementitious material that can be wholly deposited at the desired zone without loss or waste of the material in its descent into the well, and, further, to provide means for carrying the 55 material, which, also, is capable of being

disrupted, and form a good aggregate upon which the cement may collect and form a solid concrete mass when hardened, and which embeds the contiguous end of the casing, so that in the continued boring of 60 the well the tools proceed through this cement seal, which excludes the inflow of water.

It is another object of the invention to provide a container in the form of a shell 65 of frangible material capable of being readily disrupted into fragments of suitable size to form a good aggregate for the released concrete charge that may be conveyed into the desired zone in the well by 70 the frangible container. In this connection, it is desirable to provide for the proper guiding of the frangible container, or shell, through the well hole to prevent premature fracture of the shell and a loss of its cement charge, and, again, it is an object of 75 the invention to provide means for substantially taking the load from the frangible shell to reduce the liability of fracture of the shell and loss of the charge. 80

The invention possesses other objects and features of advantage, some of which, with the foregoing, will be made manifest in the following description of the preferred form of the invention which is illustrated in the 85 drawings accompanying and forming part of the specification. It is to be understood that it is not intended to limit the invention to the embodiment shown by the said drawings and description, as variations may be 90 adopted within the scope of the invention as set forth in the claims.

In the drawing, Figure 1 is a diagrammatic view showing a portion of a deep well in which the seal is produced by the present 95 method and means at the water-bearing stratum.

Fig. 2 is a side elevation and partial section of a container charged with cement ready for use in a well. 100

Fig. 3 shows a fragment of a form of the container in which it comprises a series of longitudinal sections bound together.

Fig. 4 is a detail sectional view of the upper end of one of the containers showing 105 the bail structure and a lowering apparatus attached thereto.

Fig. 5 is a detail view of the lower or leading end of a container provided with a centering guide. 110

Fig. 6 is a detail view of a portion of one of the straps or members forming a part of the bail structure.

The present method and means in its preferred embodiment for sealing a deep well, consists in the utilization of a bucket or container of any given or desired length and diameter which is capable of containing a charge of cement, either wet or dry, so that 10 the bucket and charge can be lowered bodily into a well to a given zone or level, at which the cement is released from the bucket or container to set and form an effective dam, preventing the inflow of water into 15 the well casing, and, also, embedding the contiguous end of the casing.

Particularly, the present invention involves a bucket or container made of frangible material of any suitable nature, 20 as, for instance, the bucket may be made of a shell of concrete or of fire clay, etc. Preferably, the material of the container is such as will form a good aggregate when the container is disrupted into fragments in its 25 given position in the well, and to secure fragments of desired or suitable size the container shell is weakened along suitable lines to form preferably small fragments, which the released cement charge will effectually 30 embed and bind upon after the shell is destroyed. Again, the shell is provided with a bail structure designed to carry substantially all of the load to relieve the strain from the frangible shell, and, also, a guiding device 35 is provided on the entering or leading end of the container so as to protect it against destructive contact with the contiguous well hole surface.

The method, therefore, involves the lowering of a container of any suitable length and diameter and which may be of one piece or sectional structure, such container comprising a shell 2 made of frangible material, having weakened portions as at the grooves 45 3, extending longitudinally and circumferentially about the shell to divide it into numerous small block-like portions 4 of such size as will form a good aggregate for cement. In Fig. 3, the shell is illustrated 50 as comprising longitudinal sections 2^a of semi-cylindrical form, having meeting bottom ends or transverse portions 2^b; the sections 2^a lending to the ready handling and transportation of the shell structure from the point of manufacture to a given well at which the sections may be assembled to form a complete container when bound or otherwise suitably secured, as by binding 5.

Such a container is adapted to be lowered 60 bodily into the well, as W, in which there is arranged the casing C, the bottom end of which is shown as terminating adjacent a water-bearing stratum S, at which it is desired to erect a dam or seal D of such proportions as to prevent the entry of the water

in a stratum S into the hole of the well after the latter has been completed. By the present method such a dam B is constructed by lowering the container 2 by a suitable apparatus, as the rope R, having any suitable form of releasing hook H that is attached to a bail-forming structure 6. The container, before it is lowered into the well, is charged with a batch of cement 7, either wet or dry, after which the whole is lowered into the well to the stratum S where the shell is released from the lowering apparatus R, which may be retracted, or to which may be connected a hammering or ramming device not shown, whereby the frangible shell 2 may be quite completely disrupted to produce small fragments, as the block sections 4, which will be thoroughly embedded by the cement charge 7 as it is released from the destroyed container 2.

Because of the frangibility of the container, the bail structure 6, to which the lowering apparatus is connected, is preferably of such design as to carry the weight, or most of the weight, and thus relieve the container 2 of the strains. For instance, the bail structure may consist of suitably arranged band or strap-like portions 6^a extending longitudinally of the shell of the container. The band pieces 6^a of the bail 65 may be weakened at suitable zones 6^b to facilitate the breaking up of the band pieces into desirable fragments to be effectually embedded in the cement.

To protect the frangible shell from premature destruction or fracture and the loss of the cement charge therein, the leading end of the container is preferably provided with a shoe or centering device of any suitable construction; such, for instance, as a 100 set of radially divergent arms 8 attached to the lower end of the container, the ends of the arms extending sufficiently beyond the circumference of the container to approach the surface of the casing C and thus keep 105 the shell from contact with the casing.

From the above it will be seen that the charged container can be lowered into the water stratum S below the lower end of the casing C and there deposited by the lowering apparatus, after which a suitable ram or hammer can be lowered through the casing to destroy the container 2 and release the cement 7, which will spread in all directions, and will, therefore, rise also in the 115 well hole and circumferentially embed the outer surface of the lower end of the casing C. After the cement has set, the drilling is then continued; the tool passing through the hardened dam at a point below the zone 120 of the water stratum S, the water, therefore, being barred from flowing into the well hole or casing.

What is claimed is:

1. The steps, in a method for sealing deep 125

wells against water, which consist of lowering a frangible container, charged with cement, into the well to the desired level, and then stamping the whole to destroy the container so that its fragments become embedded in the cement.

2. The steps, in a method for sealing deep wells, which consist of lowering a charge of cement, into a well, in a stone like container which can be disrupted into fragments to form aggregate, and then reducing the container to fragments to be embedded in the cement charge.

3. The method for sealing a deep well 15 against water, which consists of utilizing a container made of material adapted to disrupt into fragments serviceable as a good aggregate, lowering the container charged with cement into the well, and then disrupting the container so that the contents are released and embed the fragments.

4. The system for sealing a deep well against water, which consists in molding a container having the property of disrupting 25 into predetermined fragments forming a good aggregate for cement; lowering it, charged with cement, into a well; and then disrupting it so that the cement is discharged and embeds the fragments.

5. The system for sealing a deep well 30 against water, which consists in utilizing a container of cementitious material that will form a good aggregate for cement; lowering it, charged with cement, into a well; and then disrupting it so that the cement is discharged and embeds the fragments.

6. The system for sealing a deep well 35 against water, which consists in utilizing a container having a weakened shell of frangible material that will form a good aggregate for cement; lowering it, charged with cement, into a well; and then disrupting it so that the cement is discharged and embeds the fragments.

7. Means for sealing a deep well against water, comprising a fragile container, charged with cement, adapted to be lowered into a well and then disrupted to be embedded in the cement.

8. Means for facilitating sealing a well 40 against water, comprising a frangible container divided into small blocks adapted to be lowered, charged with cement, into the well and then disrupted.

9. Means for facilitating sealing a well 45 against water, comprising a frangible monolithic container of material forming a good

aggregate for concrete, adapted to be lowered, charged with cement, into the well and then disrupted.

10. Means for facilitating sealing a well 50 against water, comprising a frangible container adapted to be lowered, charged with cement, into the well and then disrupted; the shell of the container being weakened 55 so that it will break into suitably sized fragments.

11. Means for facilitating sealing a well 55 against water, comprising a frangible container adapted to be lowered, charged with cement, into the well and then disrupted, the container having on its leading end a centering device to guide its movement clear of the well hole surface to prevent premature fracture of the shell.

12. Means for facilitating the sealing of a deep well against water, comprising a frangible container to be lowered, charged with cement, into the well, and a bail structure combined with the container so as to 60 carry the load and relieve the shell of the weight.

13. Means for facilitating the sealing of a deep well against water, comprising a frangible container to be lowered, charged with cement, into the well, and a bail structure combined with the container so as to 65 carry the load and relieve the shell of the weight; the said bail formed of strip-like parts weakened to be broken into fragments 70 to be embedded in the concrete when the shell is disrupted in the well.

14. Means for facilitating sealing a well 75 against water, comprising a frangible container adapted to be lowered, charged with cement, into the well and then disrupted, the container comprising sections adapted for ready handling and transportation and to be assembled at the well for use.

15. A device for depositing cementitious 80 material at a predetermined level in a deep well, comprising a frangible container.

16. A device for depositing cementitious 85 material at a predetermined level in a deep well, comprising a sectional frangible container.

17. A device for depositing cementitious 90 material at a predetermined level in a deep well, comprising a frangible container of material which will form a bond with the 95 cementitious material.

In testimony whereof, I have hereunto set my hand.

HARRY C. PENDLETON.
